UNITED STATES PATENT OFFICE.

WILLIAM F. SCHACHT, OF HUNTINGTON, INDIANA.

GAME APPARATUS.

Application filed February 8, 1927. Serial No. 166,743.

This invention is a novel improvement in game apparatus which may be used in connection with ring pitching games, the game being played by pitching the rings over 5 pins or the like suitably mounted upon a base.

The principal object of the present invention is to provide a novel base for a ring pitching game having thereon a printed figure of a rabbit, clown, pumpkin, or the like, and provided with pin members attached to the base by means of novel socket members which hold the pins on the base, the rings being pitched over the pins. The base may 10 be, and preferably is, the bottom of a box of card-board or the like, to which the socket members are fastened. The game apparatus can be made cheaply by printing the figure, face, or subject, in the bottom 15 of the box, or by having labels so printed and then pasted in the bottom of the box; then inserting the sockets through openings in the bottom of the box; and then pasting a sheet of paper on the back of the box 20 over the projecting portions of the socket members so that the socket members will be held securely in place, and giving a finished appearance to the box which may be placed on a counter for sale without danger of the 25 socket members becoming loose or torn from the box.

The present invention is an improvement upon the game apparatus shown in my U. S. Letters Patent No. 1,595,527; and No. 1,616,236; and has particular reference to the novel means for connecting the pin members to the base, consisting of novel socket members preferably formed of rubber or other resilient material inserted through 40 perforations in the base from the back side thereof, the socket members preferably having bores therein adapted to receive the pin members which are retained in the bores preferably by the resiliency of the socket members, and by the suction at the inner ends of the bores set up by the entry of the pins into the bores.

Other minor objects of the invention will be hereinafter set forth.

50 I will explain the invention with reference to the accompanying drawing which illustrates some practical embodiments thereof to enable others to adopt and use the same; and will summarize in the claims

the novel features of construction, and the 55 novel combinations of parts, for which protection is desired.

In said drawings:

Figure 1 is a perspective view of the game apparatus, assembled in position for 60 use, and showing my preferred form of pin and socket member;

Fig. 2 is a section through the apparatus on the line 2—2, Fig. 1;

Fig. 3 is an enlarged transverse section 65 through my preferred form of socket member;

Fig. 4 is a top plan view thereof;

Fig. 5 is a transverse section through a modified form of socket member;

Fig. 6 is a transverse section through a further modified form of socket member, showing a pin inserted therein.

Fig. 7 is a side view of still another modified form of socket member;

Fig. 8 is a side view of still another modified form of the socket member.

As shown in the drawing, the game apparatus preferably comprises a base 1, which preferably is the bottom of a shallow 80 rectangular card-board box or the like having sides 1^a, ends 1^b, and a cover 1^c to suit. Base 1 however may be of any other material, or shape and if desired the sides 1^a, ends 1^b, and cover 1^c may be omitted.

A suitable subject, such as a rabbit, pumpkin, clown or the like is preferably printed directly upon the inner face of base 1, or if desired a label may be thus printed and pasted in position on said base. In desired 85 positions with respect to the imprinted figure on the base are circular openings 1^d preferably arranged symmetrically of the base, said openings 1^d receiving the socket members which secure the pins to the base.

Each socket member is preferably formed of rubber or other resilient material and, as shown in Figs. 3 to 8, preferably comprises a thin flat disk portion 2^a, somewhat larger in diameter than the openings or holes 1^d 100 of base 1; the disk portion 2^a having an axially disposed lug portion 2^b adapted to be inserted through opening 1^d in base 1, the diameter of lug portion 2^b being preferably slightly larger than that of the opening 1^d, in order that when inserted through the opening in base 1, the portion 2^b will resiliently engage the sides of opening 1^d and 105

normally retain the socket member in position. As shown in Figs. 1, 2, 3 and 4, in the cylindrical portion 2^b of the socket member is a vertically disposed bore 2^c which 5 may be molded or otherwise formed therein and adapted to receive a pin 3, bore 2^c being preferably of slightly smaller diameter than that of pin 3 when the socket member is made of rubber or other resilient 10 material, so that when the pin 3 is inserted into bore 2^c the walls of cylindrical portion 2^b will be bulged slightly outwardly by reason of the fact that pin 3 is larger than bore 2^c, and the outward bulging of the 15 walls of portion 2^b will further assist in securely clamping the socket member in place in base 1. Pin 3 is preferably bent into L-shaped form as shown so that when the box or base 1 is inclined against a suitable support, the rings which may be 20 pitched over the pins will not fall off.

While I prefer to make the socket members of rubber or other resilient material 25 obviously same may be made of non-resilient material such as cork, wood, metal, or the like.

After all the socket members have been 30 put in place in base 1, a sheet of paper 4 or the like is pasted on the back of the box or base 1 and over the outer faces of disk portions 2^a so that the socket members will be 35 securely held in place and also giving the base a finished appearance in order that same may be placed for sale on a counter without danger of loss, displacement, or 40 tearing out of the socket members.

As shown in Fig. 5 the axial bore in lug portion 2^b may be omitted, when the base is 45 adapted to lie flat on the floor or table in which case the pins 3 would not be necessary. If desired the portion 2^b might be made a little longer than usual to serve as 50 the pin or post over which the rings may be pitched.

In Fig. 6 the socket member is identical 55 with that shown in Fig. 5 except that a hole 2^a is drilled or molded in the side of lug portion 2^b adjacent its outer end, and adapted to receive a straight pin 3^a which when placed in position will lie parallel with the base 1. If socket member is made of resilient material, pin 3^a will be normally retained in hole 2^a by the resiliency of the 60 socket member.

In Fig. 7 the socket member is constructed identically the same as in Fig. 6 except that the projection 2^c is molded on the outer 65 end of portion 2^b to serve in place of pin 3^a thereby doing away with all metal posts or hooks. In Fig. 8 the portion 2^b is cork-shaped, this design being also used when the base is placed flat on a table and the rings thrown thereover. Other shapes may be given the lug portion 2^b.

If the socket members are made of rub-

ber or other resilient material, then the normal diameter of portion 2^b is preferably made slightly larger than that of opening 1^a in base 1; also the bores 2^c are preferably made slightly less in diameter than that of pins 3 so that when the pins are inserted into the bores 2^c the cylindrical portions 2^b will be bulged or bowed outwardly adjacent the base 1 to further secure the socket members to the base and to prevent withdrawal thereof; and at the same time pins 3 and 3^a will be retained in bores 2^c and 2^a by the resiliency of the rubber and by the suction created in the lower ends of bores 2^c and 2^a when pins 3 and 3^a are inserted therein. 70 75 80

By the above construction, the usual bolts and nuts for securing the pins to the base are dispensed with, and for ordinary purposes the above connection is found to be 85 sufficiently rigid.

The sheet of paper 4 pasted upon the back of the base over the disk portions 2^a makes the base a complete and finished article, and prevents the socket members from becoming 90 loose when placed on a counter for sale.

I do not consider my invention limited to the exact forms shown in the drawing for 95 obviously changes may be made therein within the scope of the claims.

I claim:

1. A ring pitching game apparatus of the character specified comprising a board having a plurality of openings; a plurality of resilient socket members each having a thin flat disk-like base and having a central lug portion inserted from the back of the board through the openings; the lug portion of each socket member having a bore; a pin in said bore; and a sheet affixed to the back of the board over the bases of the socket members. 100 105

2. A ring pitching game apparatus of the character specified comprising a box having a bottom, sides, ends, and a removable cover; said bottom having a design on its inner face and having a plurality of openings therethrough; a plurality of resilient socket members each having a thin flat disk-like base and having a central lug portion inserted from the back of the box through its respective opening; the lug portion of each socket member having a bore; a pin in said bore; and a sheet affixed to the back of the box over the bases of the socket members. 110 115 120

3. A game apparatus of the character specified, comprising a box having a bottom, sides, ends, and a removable cover; said bottom having a design on its inner face and a plurality of openings therethrough, a plurality of resilient socket members each having an integral thin flat disk-like base and having a central lug portion inserted from the back of the box through its respective opening; a lug por- 125 130

tion of each socket member having a radially disposed projection adjacent its outer end within the box and disposed parallel with the bottom; and a sheet affixed to the back 5 of the box over the bases of the socket members.

4. In a game apparatus as set forth in

claim 3, each socket member having a bore in its lug portion; and said projection comprising a pin retained in said bore by the 10 resiliency of the socket member.

In testimony that I claim the foregoing as my own, I affix my signature.

WILLIAM F. SCHACHT.
